DESIGN FOR A CARPET SWEEPER

Swift Miller, Wauwatosa, Wis., assignor to E. R. Wagner Manufacturing Company, Milwaukee, Wis., a corporation of Wisconsin

Application June 1, 1936, Serial No. 62,925

Term of patent 14 years

To all whom it may concern:

Be it known that I, Swift Miller, a citizen of the United States residing at Wauwatosa, in the county of Milwaukee and State of Wisconsin, have invented a new, original, and ornamental Design for a Carpet Sweeper, of which the following is a specification, reference being had to the accompanying drawing, forming a part thereof, and in which:

Figure 1 is a plan view of a carpet sweeper showing my new design;

Figure 2 is a front elevational view; and

Figure 3 is an end elevational view.

The handle and bale are shown in fragmentary conditions for convenience of illustration.

My design is characterized by a casing, sloping fore and aft and transversely, in combination with an elliptical window in the center thereof, with groups of beading extending transversely near the ends of the casing and on either side of the elliptical window.

I claim:

The ornamental design for a carpet sweeper as shown and described.

SWIFT MILLER.
